(57) **CLAIM**

We claim the ornamental design for a connector cap, as shown and described.

DESCRIPTION

FIG. 1 is a top perspective view of a connector cap;

FIG. 2 is a bottom perspective view thereof;

FIG. 3 is a top plan view thereof;

FIG. 4 is a bottom plan view thereof;

FIG. 5 is a first side view thereof; the second side view being a mirror image thereof;

FIG. 6 is a front view thereof; and,

FIG. 7 is a back view thereof.

The broken lines shown represent unclaimed subject matter and form no part of the claimed design.
